UNITED STATES PATENT OFFICE.

JOSEPH E. GIRARD, OF ROCHESTER, NEW YORK, ASSIGNOR OF ONE-HALF TO OSCAR C. SMITH, OF ROCHESTER, NEW YORK.

GRINDING AND POLISHING MACHINE.

Application filed May 27, 1920. Serial No. 384,691.

To all whom it may concern:

Be it known that I, JOSEPH E. GIRARD, a citizen of the United States, and resident of Rochester, in the county of Monroe and 5 State of New York, have invented certain new and useful Improvements in Grinding and Polishing Machines, of which the following is a specification.

The present invention relates to grinding 10 and polishing machines and more particularly to the type in which a pair of tools is provided, such tools being rotatable while in cooperation, and one of said tools having a traversing movement toward and from the 15 axis of rotation of the other tool, an object of this invention being to provide a machine which may be used for grinding spherical, cylindrical, or toric lenses of high or low curvature without changing any of the parts 20 other than the tools. Another object of the invention is to provide a construction in which the pressure between the tools will be exerted evenly throughout the entire relative movement of the tools so that the grinding 25 or polishing action will be properly distributed over the entire face of the lap. A further object of the invention is to provide for changing the throw of the traversing movement of the tools so that the greater 30 wear may be placed upon any part of the tools or lens at will. A still further object is to provide a machine of simple and inexpensive construction.

To these and other ends the invention 35 consists of certain parts and combinations of parts, all of which will be hereinafter described, the novel features being pointed out in the appended claims.

In the drawings:

40 Fig. 1 is a front view of a grinding and polishing machine constructed in accordance with this invention;

Fig. 2 is a rear view of the upper portion of the machine;

45 Fig. 3 is a section on the line 3—3, Fig. 4; Fig. 4 is a section on the line 4—4, Fig. 1; Fig. 5 is a diagrammatic view showing the machine adjusted for grinding flat lenses; and

50 Fig. 6 is a diagrammatic view, showing the machine adjusted for grinding concave lenses.

In the illustrated embodiment of the invention, 1 indicates the lower tool and 2 55 the upper tool. In this instance, the lower

tool is a grinding or polishing element while the upper tool has the lens 3 secured thereto in the usual manner. The lower tool is detachably supported on the upper end of a spindle 4 which is journaled in a stationary 60 main frame 5, whereas the upper tool has a rocking connection 6 with the lower end of a spindle 7 journaled in a frame 8 which may partake of two movements, one about an axis parallel to the axis of rotation of the spindle 7 in order to move the tool 2 toward and from the center of rotation of the tool 1 and the other about an axis at right angles to the axis of turning of the spindle 4, this last named axis preferably 65 intersecting the axis of the spindle 4 at a point in the plane of the effective face of the tool 1 at such axis. The advantage of this last named arrangement is that it is possible to exert pressure between the tools in a line which will be substantially radial to that portion of the lower tool which is substantially midway between the axis and the outer edge of the tool as shown in Fig. 70 75 80 85 90 95 100 105 110 6 of the drawings.

With the purpose in view of obtaining the foregoing movements of the frame 8, the latter has a depending sleeve 9 mounted to turn on an upstanding sleeve 10 on an intermediate frame 11, the lower end of the sleeve 9 having a flange 12 resting in an annular pocket 13 formed in the frame 11 about the sleeve 10, said flange preferably being held in this pocket by a detachable ring 14. The intermediate frame 11 has two depending lugs 15 which by pivot and securing bolts 16 connect with lugs 17 projected upwardly from the frame 5, the bolts 16 being in alignment with the axis intersecting the axis of the tool 1 at the working face of said tool to permit the spindle 7 to be adjusted and held at different angles with reference to the spindle 4 so that pressure on the work may be properly distributed.

The spindles 4 and 7 are preferably driven by a pulley 18 secured to the spindle 4 which also has a gear wheel 19 keyed thereto and meshing with an idler 20, the latter in turn meshing with a gear 21 on the counter shaft 22. This counter shaft is formed in two sections connected by a universal joint 23 arranged in line with the pivotal bolts 16, the upper section being journaled in the frame 11 and extending through the sleeve 10, its upper end being provided with a gear 24

meshing with an idler 25 journaled on the frame 8. The idler 25 meshes with a gear 26 keyed to the spindle 7 in such a manner that the spindle 7 is permitted to move longitudinally in such gear 26. The gears 19, 20, 21, 24, 25 and 26 are of such diameters that the axial speed of rotation of the spindle 4 is the same as that of the spindle 7. This driving connection permits the frame 11 to be adjusted on the pivot bolts 16 without interfering with the drive in any way whatsoever.

For the purpose of swinging the frame 8 about the upper section of the counter shaft 22 as an axis, said frame has an arm 27 clamped about its depending sleeve 9 and pivotally connected at 28 to a link 29 which in turn is secured by a bolt 30 to an eccentric point on a disk 31. This disk has a number of openings 31^a situated at different distances from its rotating center and adapted to receive the bolt 30 so that the throw of the disk may be varied and in this way the swinging action of the frame 8 about its axis parallel with the spindle 7 may be changed in order that the traversing movement of the upper tool on the lower tool may in turn be varied. The disk 31 is preferably supported on the upper end of a shaft 32 journaled in the frame 11 and having a worm wheel 33 at its lower end engaged by a worm 34 on a shaft 35, said shaft also carrying a bevel gear 36 which meshes with a bevel gear 37 on the upper section of the counter shaft 22. In this way the traversing movement of the tool 2 is obtained from the pulley 8 which also drives the spindle 4, thus establishing a time relation between the rotation of the tools and the traversing movement.

With the purpose in view of holding the tools together with yielding pressure, a tubular housing 38 is projected upwardly from the frame 8 and is closed by a cap 39 which is externally threaded and engages internal threads in the tubular projection 38. A helical spring 40 surrounds the shaft of the spindle 7 within the tubular projection 38 and has one end abutting the cap or bushing 39 and the other end abutting a collar 41 which bears against anti-friction balls 42 supported on the flange 43 of the spindle 7. It is apparent that the adjustment of the cap 39 will vary the compression of the spring 40 and in this way vary the pressure with which the tool 2 cooperates with the tool 1. With the purpose in view of permitting the tool 2 to be moved away from the tool 1, a lever 44 is pivoted at 45 to the cap 39 and has a bifurcated end 46 which lies below a nut 47 on the upper end of the spindle 7. Downward pressure on the outer end of the lever 44 will move the spindle 7 axially against the spring 40 and permit the tool 2 to be detached from the

spindle 7. The flange 43 limits the movement of the spindle 7 toward the tool 1 after the tool 2 has been removed.

The operation of the invention will be understood from the foregoing, but it may be summarized as follows:

Tools of proper curvature are connected to the spindles 4 and 7 and thereafter the frame 11 is adjusted through the bolts 16 so that the axis of the shaft 7 will be perpendicular to that portion of the lower tool which is midway between the axis of said lower tool and the outer periphery of such tool. The screw 30 is connected to that opening of the disk 31 which will give to the tool the desired traversing movement. Upon the starting of the machine, the tools 1 and 2 will rotate in the same direction and at the same speed. At the same time the tool 2 will swing toward and from the axis of the tool 1. Should it be found that the traversing movement of the tool 2 produces wear upon the tool or the lens at one point of the movement, the traversing movement is varied by shifting the arm 27 on the depending sleeve 9 through the collar on the inner end of the arm, said collar being held in its adjusted position by the set screw 27^a, which will counteract the unequal wear. To vary the length of the traversing movement for tools of different diameters, the screw 30 is fitted in the desired opening 31^a. Owing to the fact that the frame 8 is adjustable about an axis at right angles to the axes of rotation of both of the tools, such axis intersecting such axes at the surface being ground or polished, it is possible to exert pressure between the tools in a line which will intersect the curved face radial to a point midway between the center of the polishing or grinding tool on the outer edge of such tool, thus reducing unequal wear in grinding or polishing to a minimum. The traversing movement of the tool may be varied in length so that the grinding operation may be confined to any desired area. The machine as a whole is simple in operation and inexpensive to manufacture.

What I claim as my invention and desire to secure by Letters Patent is:

1. A lens grinding and polishing machine comprising a pair of rotary tools, a main frame on which one of said tools turns, a frame on which the other tool turns, means for supporting said second frame to permit it to be adjusted relatively to the first named frame about an axis at right angles to the axis of turning of the tool on the main frame and intersecting the center of such tool at a point substantially in a plane with the operative face of the tool and driving connection between the tools causing them to rotate at the same axial speed.

2. A lens grinding and polishing machine comprising a pair of rotary tools, a main

- frame on which one of said tools turns, a frame on which the other tool turns, means for supporting said second frame to permit it to be adjusted relatively to the first named
- 6 frame about an axis at right angles to the axis of turning of the tool on the main frame and intersecting the center of such tool at a point substantially in a plane with the operative face of the tool, means for
- 10 swinging the second frame about an axis parallel with the axis of rotation of the tool on said swinging frame and driving connection between the tools causing them to rotate at the same axial speed.
- 15 3. A lens grinding and polishing machine comprising a pair of rotary tools, two frames, means for adjusting one frame with reference to the other frame so that the angle of the axis of turning of one tool
- 20 with reference to the axis of turning of the other tool may be changed, means shifting one tool back and forth with reference to the other tool in a plane at right angles to the axis of turning of the shifted tool, and driving
- 25 connections between the tools causing them to rotate at the same axial speed.
4. A lens grinding or polishing machine comprising a pair of rotary tools, a main frame on which one of said tools turns a sec-
- 30 ond frame on which the other tool turns, mounted to turn about an axis parallel with the axis of turning of the tool carried thereby, and an intermediate frame on which
- 35 said second mentioned frame turns, said in-
- 40 termediate frame being mounted to swing about an axis at right angles to the axis of turning of the tool on the main frame, and driving connection between the tools embodying a shaft having two sections and a
- 45 universal joint between the sections, one of said sections being journaled in the first mentioned frame and the other of said sections being journaled in the intermediate frame.
- 50 5. A lens grinding or polishing machine comprising a pair of rotary tools, a main frame on which one of said tools turns a sec-
- 55 ond frame on which the other tool turns, mounted to turn about an axis parallel with the axis of turning of the tool carried thereby, an intermediate frame on which said sec-
- 60 ond mentioned frame turns, said intermediate frame being mounted to swing about an
- 65 axis at right angles to the axis of turning of the tool on the main frame, driving con-
- 70 nection between the tools embodying a shaft having two sections and a universal joint between the sections, one of said sections being journaled in the first mentioned frame and the other of said sections being journaled in the intermediate frame, and a
- 75 driving connection between the upper section of said shaft and the second mentioned frame for swinging the latter on the inter-
- 80 mediate frame.
- 85 6. A grinding or polishing machine comprising a pair of rotary tools, a main frame on which one of said tools turns, a second frame on which the other of said tools turns, an intermediate frame pivotally connected to the main frame to swing about an axis at right angles to the axis of turning of the tool on said frame, said intermediate frame having a sleeve projecting upwardly therefrom and forming a bearing on which
- 90 the second frame may turn about an axis parallel with the axis of rotation of the tool on the second frame, and a driving connection between the tools embodying a shaft having two sections and a universal joint, one of the sections turning in the main frame and the other turning in the sleeve of the intermediate frame, the universal joint being situated in line with the axis about which the intermediate frame is adjustable on the main frame.
- 95 7. A lens grinding or polishing machine comprising a pair of rotary tools, a main frame on which one of said tools turns, a second frame on which the other of said tools turns, mounted to turn about an axis parallel with the axis of turning of the tool carried thereby, an intermediate frame on which the second mentioned frame turns, said intermediate frame being mounted to
- 100 turn about an axis at right angles to the axis of turning of the tool of the second mentioned frame, means for oscillating the second mentioned frame on the intermediate frame, said means being mounted upon the intermediate frame so as to shift with said frame in all adjusting positions of the latter and driving connection between the tools causing them to rotate at the same axial speed.

JOSEPH E. GIRARD.
